UNITED STATES PATENT OFFICE.

EDWARD COOPER TAYLOR, OF NEW YORK, N. Y.

DESIGN FOR CASING FOR TRAFFIC SIGNALS.

Application filed November 25, 1922. Serial No. 4,402. Term of patent 7 years.

To all whom it may concern:

Be it known that I, EDWARD COOPER TAYLOR, a citizen of the United States, residing at the city of New York, in the county of Bronx and State of New York, have invented a new, original, and ornamental Design for Casing for Traffic Signals, of which the following is a specification, reference being had to the accompanying drawing, forming part thereof.

Figure 1 is a face view of a casing for traffic signal, showing my new design, and Fig. 2 is an end view thereof, looking toward the left end of Fig. 1.

I claim:

The ornamental design for a casing for traffic signals, as shown.

EDWARD COOPER TAYLOR.
